METHOD OF RECEIVING, AMPLIFYING, AND DETECTING OSCILLATORY ENERGY

Application filed May 1, 1928. Serial No. 274,235.

This invention relates to the method of receiving, amplifying and detecting high frequency electrical oscillatory energy by amplifying both halves of the incoming wave, further amplifying the amplified wave by a regenerative coupling to the same stage of amplification and simultaneously detecting both halves of the amplified wave.

The main purpose of this invention is to convert the incoming high frequency wave to a wave of audible frequency in the most efficient manner. It is well known in the art that appreciable losses are incurred in the couplings between stages of amplification together with the attendant difficulty, if one control is desired, of tuning the successive stages.

In this invention it is proposed to receive, amplify and detect the incoming wave in one stage, the audible frequency resulting therefrom being further amplified, if desired, in the usual manner. By this means only one tuning condenser and one stage of high frequency amplification is required. The antenna is of the aperiodic type, two or three separate antennas being required for maximum results.

The circuit used is of the regenerative type and can be made very selective by the proper adjustment between the source of incoming oscillations and the input circuit and by minimizing the amount of resistance in the tuned circuits. In view of the high degree of selectivity which may be obtained, it is possible and may even be desirable in receiving apparatus remotely located from the broadcasting station, to interpose between the circuit arrangement disclosed herein and the source of incoming oscillations one or more stages of untuned radio frequency amplification.

The principal circuit connections of the apparatus are shown in the drawing, where coil 1 represents the source of the incoming oscillations. Energy from coil 1 is induced to coils 2 and 3 which are connected together with their fields aiding, the other leads from the coils 2 and 3 being connected to the variable condenser 8 and the grids 9 and 10. Now as a potential is impressed upon grid 9 a potential of opposite polarity is impressed upon grid 10 causing a corresponding in-

crease and decrease in the current in plate leads 11 and 12. These leads are connected to coils 4 and 5 in such manner that the change in plate currents cause a change in the fields of coils 4 and 5 to aid the currents in coils 2 and 3. Sufficient capacity exists between coils 2 and 4, 3 and 5, and the windings of coils 6 and 7 to permit the circuit to regenerate, the undesirable oscillations being minimized by the radio frequency choke coils 6 and 7. The grids 9 and 10 are connected to the filaments of the tubes 16 and 17 at a center tap between coils 2 and 3 and through grid capacity and associated grid leak resistance 13. Grid capacity and grid leak resistance 13 thus serve both grids in common. Simultaneous detection takes place through both tubes in parallel.

I claim:

1. The method of receiving, amplifying and detecting high frequency electrical oscillatory energy which comprises an amplification of both halves of the wave of the incoming energy, each half wave being further amplified by the regenerative coupling of the other half wave and a detection of both amplified waves simultaneously.

2. In a radio receiving system, the combination of a plurality of windings inductively coupled, a tuning condenser connected across the grid leads of two vacuum tubes, the grid and plate leads of said vacuum tubes connecting with the said plurality of windings, a grid condenser and grid leak resistance common to the grids of both of said vacuum tubes, radio frequency choke inductances interposed between the plate leads and the common audio frequency lead, said combination detecting and regenerating both halves of the incoming wave.

3. In a radio receiving system, the combination of an aperiodic antenna, a plurality of windings inductively coupled, a tuning condenser connected across the grid leads of two vacuum tubes, the grid and plate leads of said vacuum tubes connecting with the said plurality of windings, a grid condenser and grid leak resistance common to the grids of both of said vacuum tubes, radio frequency choke inductances interposed be-

tween plate leads and the common audio frequency lead said combination detecting and regenerating both halves of the incoming wave.

- 5 4. A selective receiving system for receiving oscillations of radiant energy comprising an antenna circuit, an input circuit coupled thereto and resonant to the frequency to be detected, two grids having a common 70
10 grid to filament lead and connected in diametric phase relation to each other to said input circuit, two plates symmetrically associated with said grids, said plates being connected together through a series circuit 75
15 coupled in phase to said input circuit and each of said plates being connected to a circuit converging on a common plate to filament lead.

5. A selective receiving system for receiving 20 oscillations of radiant energy comprising an antenna circuit, an input circuit coupled thereto and resonant to the frequency to be detected, two grids having a common 80
25 grid to filament lead, a capacitance and resistance in shunt and interposed in said lead, said grids connected in diametric phase relation to each other to said input circuit, two plates symmetrically associated with said 85
30 grids, said plates being connected together through a series circuit coupled in phase to said input circuit and each of said plates being connected to a circuit converging on a common plate to filament lead.

6. A selective receiving system for receiving 35 oscillations of radiant energy comprising an incoming source of current variations, an input circuit coupled thereto and resonant to the frequency to be detected, two grids having a common grid to filament lead, a 90
40 and connected in diametric phase relation to each other to said input circuit, two plates symmetrically associated with said grids, said plates being connected together through a series circuit coupled in phase to said input 95
45 circuit and each of said plates being connected to a circuit converging on a common plate to filament lead.

7. A selective receiving system for receiving 50 oscillations of radiant energy comprising an incoming source of current variation, an input circuit coupled thereto and resonant to the frequency to be detected, two grids having a common grid to filament lead, a 100
55 capacitance and resistance in shunt and interposed in said lead, said grids connected in diametric phase relation to each other to said input circuit, two plates symmetrically associated with said grids, said plates being connected together through a series circuit 105
60 coupled in phase to said input circuit and each of said plates being connected to a circuit converging on a common plate to filament lead.

8. A selective receiving system for receiving 65 oscillations of radiant energy comprising

an antenna circuit, an input circuit coupled thereto and resonant to the frequency to be detected, two grids having a common grid to filament lead and connected in diametric phase relation to each other to said input circuit, two plates symmetrically associated with said grids, said plates being connected together through a series circuit coupled in phase to said input circuit and each of said plates being connected to a circuit converging on a common plate to filament lead, a pair of filament circuits and a pair of impedances interposed symmetrically in each pair of said filament circuits between sections of electronic emission and junction of 80
75
80 said common leads.

9. A selective receiving system for receiving oscillations of radiant energy comprising an antenna circuit, an input circuit coupled thereto and resonant to the frequency to be detected, two grids having a common grid to filament lead, a capacitance and resistance in shunt and interposed in said lead, said grids connected in diametric phase relation to each other to said input circuit, two plates symmetrically associated with said grids, said plates being connected together through a series circuit coupled in phase to said input circuit and each of said plates being connected to a circuit converging on a common plate to filament lead, a pair of filament circuits and a pair of impedances interposed symmetrically in each pair of said filament circuits between sections of electronic emission and junction of said common leads.

10. A selective receiving system for receiving oscillations of radiant energy comprising an incoming source of current variations, an input circuit coupled thereto and resonant to the frequency to be detected, two grids having a common grid to filament lead and connected in diametric phase relation to each other to said input circuit two plates symmetrically associated with said grids, said plates being connected together through a series circuit coupled in phase to said input circuit and each of said plates being connected to a circuit converging on a common plate to filament lead, a pair of filament circuits and a pair of impedances interposed symmetrically in each pair of said filament circuits between sections of electronic emission and junction of said common leads.

11. A selective receiving system for receiving oscillations of radiant energy comprising an incoming source of current variation, an input circuit coupled thereto and resonant to the frequency to be detected, two grids having a common grid to filament lead, a capacitance and resistance in shunt and interposed in said lead, said grids connected in diametric phase relation to each other to said input circuit, two plates symmetrically associated with said grids, said plates being connected together through a series circuit coupled in 120
115

phase to said input circuit and each of said plates being connected to a circuit converging on a common plate to filament lead, a pair of filament circuits and a pair of impedances interposed symmetrically in each pair of said filament circuits between sections of electronic emission and junction of said common leads.

12. In a radio receiving system, a detector and regenerative amplifier stage, an incoming source of current variations an input circuit coupled thereto and resonant to the frequency to be detected, two grids having a common grid to filament lead, a capacitance and resistance in shunt and interposed in said lead, said grids connected in diametric phase relation to each other to said input circuit, two plates symmetrically associated with said grids, said plates being connected together through a series circuit coupled in phase to said input circuit and each of said plates being connected to a circuit converging on a common plate to filament lead and an outgoing circuit associated with said common plate to filament lead.

13. In a radio receiving system, a detector and regenerative amplifier stage, an incoming source of current variations, an input circuit coupled thereto and resonant to the frequency to be detected, two grids having a common grid to filament lead, a capacitance and resistance in shunt and interposed in said lead, said grids connected in diametric phase relation to each other to said input circuit, two plates symmetrically associated with said grids, said plates being connected together through a series circuit coupled in phase to said input circuit and each of said plates being connected to a circuit converging on a common plate to filament lead and an outgoing circuit associated with said common plate to filament lead, a pair of filament circuits and a pair of impedances interposed symmetrically in each pair of said filament circuits between sections of electronic emission and junction of said common leads.

14. In a radio receiving system, a regenerative amplifier stage, an incoming source of current variations, an input circuit coupled thereto and resonant to the frequency to be detected, two grids having a common grid to filament lead, a negative potential for said grids interposed in said lead, said grids connected in diametric phase relation to each other to said input circuit, two plates symmetrically associated with said grids, said plates being connected together through a series circuit coupled in phase to said input circuit and to an outgoing circuit each of said plates being connected to a circuit converging on a common plate to filament lead.

15. In a radio receiving system, a regenerative amplifier stage, an incoming source of current variations, an input circuit coupled thereto and resonant to the frequency to be

detected, two grids having a common grid to filament lead, a negative potential for said grids interposed in said lead, said grids connected in diametric phase relation to each other to said input circuit, two plates symmetrically associated with said grids, said plates being connected together through a series circuit coupled in phase to said input circuit and to an outgoing circuit each of said plates being connected to a circuit converging on a common plate to filament lead, a pair of filament circuits and a pair of impedances interposed symmetrically in each pair of said filament circuits between sections of electronic emission and junction of said common leads.

16. A filter circuit comprising an incoming source of current variations, an input circuit coupled thereto and transparent to a band of frequencies to be amplified and opaque to others, two grids having a common grid to filament lead and connected in diametric phase relation to each other to said input circuit, two plates symmetrically associated with said grids, said plates being connected together through a series circuit coupled in phase to said input circuit and to an outgoing circuit each of said plates being connected to a circuit converging on a common plate to filament lead.

17. A filter circuit comprising an incoming source of current variations, an input circuit coupled thereto and transparent to a band of frequencies to be amplified and opaque to others, two grids having a common grid to filament lead and connected in diametric phase relation to each other to said input circuit, two plates symmetrically associated with said grids, said plates being connected together through a series circuit coupled in phase to said input circuit and to an outgoing circuit each of said plates being connected to a circuit converging on a common plate to filament lead, a pair of filament circuits and a pair of impedances interposed symmetrically in each pair of said filament circuits between sections of electronic emission and junction of said common leads.
